[57] CLAIM

The ornamental design for a bag holder, as shown and described.

DESCRIPTION

FIG. 1 is a top front view of a bag holder of my new design with a bag supported for use;

FIG. 2 is a top perspective view from the left of the bag holder, the view from the right being a mirror image, the back being plain and unornamented;

FIG. 3 is a top left perspective view of a frame of the bag holder;

FIG. 4 is a perspective view of a bag suspension member of the bag holder; and,

FIG. 5 is a perspective view showing the bag holder in a preliminary position.
